UNITED STATES PATENT OFFICE.

KARL OCHS, OF BERLIN-CHARLOTTENBURG, GERMANY, ASSIGNOR TO SIEMENS & HALSKE, A. G., OF SIEMENSSTADT, NEAR BERLIN, GERMANY, A CORPORATION OF GERMANY.

APPARATUS FOR ELECTROLYSIS OF ALKALINE CHLORIDS.

1,138,400.

Specification of Letters Patent.

Patented May 4, 1915.

Application filed November 13, 1914. Serial No. 872,051.

To all whom it may concern:

Be it known that I, KARL OCHS, a German citizen, residing at Berlin-Charlottenburg, Germany, have invented certain new and useful Improvements in Apparatus for Electrolysis of Alkaline Chlorids, of which the following is a specification.

This invention relates to a new process for electrolytically obtaining alkaline chlorides according to the method using a horizontal diaphragm and has for its principal object to prevent the formation of hypochlorite ($NaOCl$) which takes place during the entrance of the generated chlorin into the lower parts of the liquid space. Ordinarily this is avoided by causing exact layers to be formed in the liquid, for instance by providing a thick layer of sulfate of barium ($BaSO_4$) and asbestos upon the asbestos cloth which serves for filtration. Although in this manner the formation of hypochlorite is almost prevented, for carrying this method into effect, however, a considerable increase of voltage will be required.

By my present invention more particularly a good layer formation in the liquid without employing a layer of the above kind is attained by subdividing the liquid space above the asbestos cloth into a greatest possible number of small partitions. This may for instance be accomplished by providing above the filtering cloth parallel transverse walls in the vat or container, said walls being of a material which resists the influence of chlorin and alkalies, such as glass, porcelain, clay, or an artificial mass made from cement and asbestos. These transverse walls may be fastened to the container for instance by inserting the same into proper grooves provided in the walls of the container.

In the accompanying drawing Figure 1 is a diagrammatic elevation partly in section through an apparatus for electrolyzing alkaline chlorids by means of a horizontal diaphragm comprising the above additional transverse walls according to my invention, Fig. 2 a plan view of said transverse walls of Fig. 1 and Figs. 3, 4 and 5 represent the

arrangement of further hollow bodies provided within said transverse walls subdividing the liquid space of the container of the apparatus.

The transverse walls, which are indicated in the drawing by the letter *a*, rest upon the asbestos cloth and cathode net *b*, beneath the anode *c*, and will prevent any motion in the liquid within the container *B* and consequently prevent the chlorin from entering into the lower layer above the diaphragm.

A further subdivision of the space containing the liquid of the apparatus is accomplished by hollow bodies *d*, as shown in Figs. 3, 4 and 5. These bodies may have any desired cross-section, for instance that of a hollow cylinder, and besides forming partitions in the liquid space will simultaneously serve to keep the transverse walls *a* in position. Fig. 4 shows an arrangement without transverse walls *a*, whereby hollow bodies *d* alone are employed in a regular or irregular disposition for forming partitions in the liquid space.

A subdivision or partitioning of the liquid space may also be attained by employing non-rigid means in such a manner, for instance as shown in Fig. 5, cords or strings *e* of asbestos are provided upon the asbestos filter to form a plane net or a web with a plurality of layers. In the latter case the several layers are preferably displaced relatively to each other as indicated at *F* in Fig. 5. This net or web of asbestos may further be weighted by hollow bodies or transverse walls as desired.

It is to be understood that by the term "partitions" as employed in the specification and claim I include any of the forms disclosed in the description and drawing whereby a free circulation of the liquid in the neighborhood of the diaphragm is prevented.

Having thus described my invention I claim as new and desire to secure by Letters Patent of the United States:—

Apparatus for the electrolysis of alkaline chlorids comprising in combination a liquid container, suitable positive and negative electrodes above and below, a porous dia-

phragm extending across the space between said electrodes, and vertical partitions disposed adjacent to the upper surface of said porous diaphragm and submerged in the liquid between the positive electrode and said porous diaphragm said partitions being of such height compared with their distance from each other as to prevent bodily

motion of the liquid in the space adjacent to the diaphragm.

In testimony whereof I affix my signature in presence of two witnesses.

KARL OCHS.
